AUTOMATIC WEB REGISTER CORRECTING
MEANS FOR PRINTING PRESSES

Joseph E. Meyer, Westerly, R. I., assignor to C. B.
Cottrell & Sons Company, Westerly, R. I., a
corporation of Delaware

Application April 2, 1943, Serial No. 481,528

22 Claims. (Cl. 101—225)

In rotary web perfecting printing presses in which quick drying inks and drying units are employed, the web lead between the first and second printing units is necessarily long and the traveling web develops a tendency to shift laterally in the one or the other direction before it reaches the second printing unit with the result that the printing on the second side of the web will be out of line with the printing on the first side of the web. This tendency of the traveling web to shift laterally is exaggerated when the first side printing is heavy along one side of the web and light along the other side.

In rotary web perfecting printing presses where the first and second printing units are located in line with the press this tendency of the web to shift laterally has heretofore been corrected by manually tilting one of the web feed rolls. This method is unsatisfactory as the tilting of the web feed roll puts an excess strain along one edge of the web tending to break the web and thus causing a loss of paper and production. This method is also unsatisfactory in that the defect in the printing is not detected until the product has been printed on the other side, folded and delivered. It is necessary, therefore, to run considerable waste or defective product before the trouble can be found and corrected.

The object of my invention is to provide means controlled by the lateral shifting of the web for automatically correcting its loss of lateral register as it passes from the first printing unit to the second printing unit, thereby preventing great waste of paper and loss of time and production.

A further object is to provide means for automatically and simultaneously correcting loss of longitudinal register of the traveling web due to the correction for lateral register.

A further object is to provide manually operated means acting on the web for initially bringing the first side printed web into approximately correct register with the second or perfecting printing unit to permit the proper functioning of the automatic web register correcting means.

A practical embodiment of my invention is represented in the accompanying drawings in which

Fig. 1 represents a diagrammatic top plan view of my invention incorporated in a multicolor rotary web perfecting printing press adapted for use with quick drying inks and drying apparatus;

Fig. 2 represents a side view of the same;

Fig. 3 represents a detail top plan view on an enlarged scale of the first web turning bar and its adjacent parts;

Fig. 4 represents a section taken in the plane of the line IV—IV of Fig. 3, looking in the direction of the arrows;

Fig. 5 represents a section taken in the plane of the line V—V of Fig. 3, looking in the direction of the arrows.

Fig. 6 represents a detail top plan view on the same scale as Fig. 3, of the second turning bar and the web reversing roller and their operative connections;

Fig. 7 represents a detail side view of the same;

Fig. 8 represents a section taken in the plane of the line VIII—VIII of Fig. 6, looking in the direction of the arrows;

Fig. 9 represents a section taken in the plane of the line IX—IX of Fig. 6, looking in the direction of the arrows; and

Fig. 10 represents a diagrammatic view of a photoelectric unit which is controlled by the lateral shifting of the traveling web to control the operation of the motor which is operatively connected to the second turning bar and the web reversing roller.

The web W is directed from its source of web supply, not shown herein, by suitable guide rollers G through the first printing unit, the first drying apparatus, the web register correcting unit, the second printing unit and the second drying apparatus, to a suitable delivery, also not shown herein. These first and second printing units and their drying apparatuses are arranged in line with the press, the first printing unit being shown as comprising an impression cylinder P and its several form cylinders p; and the second or web perfecting printing unit as comprising an impression cylinder P' and its several form cylinders p'.

The first drying apparatus is shown as comprising a heating drum D and its web cooling cylinders d; and the second drying apparatus as comprising a heating drum D' and the web cooling cylinders d'.

The means controlled by the lateral shifting of the web for automatically correcting the loss of register of the web as it passes from the first printing unit to the second printing unit is constructed, arranged and operated as follows:

The web register correcting unit is shown as comprising first and second web turning bars 1 and 2 and their coacting web reversing roller 3. The first turning bar directs the web W as it comes from the first printing unit, outwardly at

right angles to the press to and around the roller 3, which roller reverses the travel of the web and directs it inwardly at right angles to the press, to and around the second turning bar 2 which directs the web back into line with the press before the web reaches the second printing unit.

As the web leaves the second turning bar 2 it passes over the scanning roller 4 which coacts with the scanning head 5 and the source of light 5' of the photoelectric unit 6, which unit may be of any well known or approved construction. The peripheral surface of this scanning roller 4 may be made non-light reflecting to contrast it with the light reflecting surface of the web, to ensure the energization of the photoelectric unit when the web shifts laterally in either direction from its true path on its way to the second printing unit, as will be hereinafter more fully set forth.

The scanning head 5 has two internal divisions denoted by A and A' in Fig. 10; the division A being sensitive to light reflected from the web W when it shifts to the left of its median position; and the division A' being sensitive to absorption of light by the dark surface of the roller 4, when the web W shifts to the right of its median position.

The normally deenergized reversible electric motor M is operatively connected to both ends of one of the web turning bars, in the present instance the second turning bar 2, for automatically correcting loss of lateral register of the web. This motor M is also operatively connected to the web reversing roller 3 for automatically correcting loss of longitudinal or circumferential register caused by the correction of the loss of lateral register of the web.

The motor shaft m is operatively connected to the cross shaft 7 through a worm and gear 8 and 9. This shaft 7 is mounted in the side frames F, F' and it is operatively connected through the spiral gears 10, 11 and 10', 11' to the longitudinally disposed shafts 12, 12'. The shaft 12 is threaded into an adjustable sleeve 13 having a threaded connection with a block 14 slidably mounted in a suitably supported fixed bracket 15. A lock nut 16 serves to lock the sleeve 13 to its block 14. The longitudinal shaft 12' is directly threaded into its block 14' which is slidable in the fixed bracket 15'.

The opposite ends of the turning bar 2 are adjustably secured by bolts 11, 17' to their respective slidable blocks 14, 14'.

The cross shaft 7 is operatively connected through the spur gears 18 and 19 to the cross shaft 20, which cross shaft is connected through the gears 21, 22 to the longitudinally disposed shaft 23. This shaft 23 is operatively connected through the two pairs of spiral gears 24, 25 and 24', 25' to the cross shafts 26, 26' which are rotatably mounted in suitably supported fixed brackets 27, 27' and are threaded into end bearings 28, 28' for the shaft 3* of the web reversing roller 3. These bearings 28, 28' are slidable in the suitably supported fixed brackets 29, 29'.

The web turning bars 1 and 2 and their coacting web reversing roller 3 may be initially adjusted to bring them into approximate register, within the range of operation of the web register controlled means for automatically correcting the loss of register of the web, as follows:

The first web turning bar 1 has its ends adjustably secured by bolts 30, 30' to blocks 31, 31' slidable in suitably supported fixed brackets 32, 32'. Screw shafts 33, 33' are rotatably mounted in suitably supported fixed brackets 34, 34' and

the inner ends of these shafts are threaded into the blocks 31, 31'. The outer ends of these screw shafts 33, 33' may be squared to removably receive a suitable hand crank 35.

5 The second web turning bar 2 and the web reversing roll 3 may be simultaneously adjusted in their desired relative positions by providing the cross shaft 7 with a suitable hand wheel 36.

10 The individual adjustment of one end of the second web turning bar 2 may be accomplished by releasing the lock nut 16, turning the adjusting sleeve 13 in its block 14 and then tightening the lock nut 16 to secure the sleeve in its adjusted position.

15 In operation: as long as the traveling web remains in its correct side register all of the parts of the automatic side register control will be inoperative. Should this side register be lost by the lateral shifting of the web in either direction this loss of register is immediately corrected as follows:

20 If this shifting of the web be to the division A of the scanning head 5 the photoelectric unit is actuated by the reflection of light from the surface of the traveling web and the circuit passes through the battery B and the holding coil C to close the relay D. This will close the armature and field circuits of the motor M, causing it to rotate in the direction to automatically adjust the scanning web turning bar 2 and the roller 3 for bringing the web back into proper register. When the web returns to its correct register the scanning head 5 operates to open the circuit A, B, C and thereby demagnetizes the holding coil C of the relay D. This opens the armature and field circuits and stops the motor.

25 When the web shifts to the division A' the scanning head 5 is actuated by the absorption of light from the dark peripheral surface of the scanning roller 4. The circuit A', B, C' is then closed, operating the relay D' which closes the armature and field circuits of the motor M and causes the motor to rotate in the opposite direction to automatically adjust the second turning bar 2 and its coacting roller 3 simultaneously for bringing the web back into its proper register with respect to the second printing unit. When the web returns to its correct register the scanning head 5 operates to open the circuit A', B, C', thereby demagnetizing the holding coil C' of the relay D'. This will open the armature and field circuits and thus stop the motor.

30 It will be observed that the motor field leads from the relay D' are reversed, relative to polarity, to those from the relay D, but the armature leads are not reversed. This provides a condition which causes the motor to revolve clockwise when started by one relay and anti-clockwise when started by the other relay. It will thus be seen that the other turning bar and its coacting roller may be moved in one direction or the other automatically, to correct the lateral shifting of the web in either direction out of its true side register.

35 While I have shown one of the turning bars, in the present instance the second turning bar 2, as automatically adjustable lengthwise of the press, it is obvious that one of the turning bars, as for instance the second turning bar 2, may equally well be automatically adjustable crosswise of the press, to accomplish the correction for loss of side register of the web.

40 It is evident that various changes may be resorted to in the construction, form and arrangement of the several parts without departing from the spirit and scope of my invention, and hence

I do not intend to be limited to the particular embodiment herein shown and described, but

What I claim is:

1. In a rotary web perfecting printing press, first and second printing units arranged in line with the press, means for passing the web through said printing units, and a web register correcting unit controlled by the lateral shifting of the web, and including means for automatically correcting the loss of lateral register of the web and for automatically and simultaneously correcting the loss of longitudinal register of the web due to its correction for loss of lateral register, as the web passes from the first printing unit to the second printing unit.

2. In a rotary web perfecting printing press, first and second printing units arranged in line with the press, means for passing the web through said printing units, and an electrically operated web register correcting unit controlled by the lateral shifting of the web, and including means for automatically correcting the loss of lateral register of the web and for automatically and simultaneously correcting the loss of longitudinal register of the web due to its correction for loss of lateral register, as the web passes from the first printing unit to the second printing unit.

3. In a rotary web perfecting printing press, first and second printing units arranged in line with the press, means for passing the web through said printing units, and a web register correcting unit controlled by the lateral shifting of the web, for automatically correcting the loss of lateral register of the web and for automatically and simultaneously correcting the loss of longitudinal register of the web due to its correction for loss of lateral register, as the web passes from the first printing unit to the second printing unit, the said web register correcting unit including two diagonal turning bars and their co-acting web reversing roller, one of said bars and said roller being automatically adjustable simultaneously.

4. In a rotary web perfecting printing press, first and second printing units arranged in line with the press, means for passing the web through said printing units, and an electrically operated web register correcting unit controlled by the lateral shifting of the web, for automatically correcting the loss of lateral register of the web and for automatically and simultaneously correcting the loss of longitudinal register of the web due to its correction for loss of lateral register, as the web passes from the first printing unit to the second printing unit, the said web register correcting unit including two diagonal turning bars and their co-acting web reversing roller, one of said bars and said roller being automatically adjustable simultaneously.

5. In a rotary web perfecting printing press, first and second printing units arranged in line with the press, means for passing the web through said printing units, and a web register correcting unit controlled by the lateral shifting of the web, for automatically correcting the loss of lateral register of the web and for automatically and simultaneously correcting the loss of longitudinal register of the web due to its correction for loss of lateral register, as the web passes from the first printing unit to the second printing unit, the said web register correcting unit including two diagonal turning bars and their co-acting web reversing roller, and a reversible motor for automatically adjusting one of the turning bars and the roller simultaneously.

6. In a rotary web perfecting printing press,

first and second printing units arranged in line with the press, means for passing the web through said printing units, and an electrically operated web register correcting unit controlled by the lateral shifting of the web, for automatically correcting the loss of lateral register of the web and for automatically and simultaneously correcting the loss of longitudinal register of the web due to its correction for loss of lateral register, as the web passes from the first printing unit to the second printing unit, the said last named means including two diagonal turning bars and their co-acting web reversing roller, and a reversible motor for automatically adjusting one of the turning bars and the roller simultaneously.

7. In a rotary web perfecting printing press, first and second printing units arranged in line with the press, means for passing the web through said printing units, and a web register correcting unit controlled by the lateral shifting of the web, for automatically correcting the loss of lateral register of the web and for automatically and simultaneously correcting the loss of longitudinal register of the web due to its correction for loss of lateral register, as the web passes from the first printing unit to the second printing unit, the said web register correcting unit including two diagonal turning bars and their co-acting web reversing roller, a photoelectric unit and a motor set in motion thereby, said motor being operatively connected to both ends of one of said turning bars and to both ends of the roller for simultaneously adjusting them.

8. In a rotary web perfecting printing press, first and second printing units arranged in line with the press, means for passing the web through said printing units, and a web register correcting unit controlled by the lateral shifting of the web, for automatically correcting the loss of lateral register of the web and for automatically and simultaneously correcting the loss of longitudinal register of the web due to its correction for loss of lateral register, as the web passes from the first printing unit to the second printing unit, the said web register correcting unit including two diagonal turning bars and their co-acting web reversing roller, a photoelectric unit and a motor set in operation thereby for automatically adjusting both ends of one of said turning bars and both ends of the roller simultaneously.

9. In a rotary web perfecting printing press, first and second printing units arranged in line with the press, a web register correcting unit comprising first and second diagonal turning bars and their co-acting web reversing roller, means for passing the web through the first printing unit, around the first turning bar, the roller, the second turning bar and through the second printing unit, and means controlled by the lateral shifting of the web for automatically and simultaneously adjusting both ends of one of the turning bars without changing its angularity to correct the loss of lateral register of the web.

10. In a rotary web perfecting printing press, first and second printing units arranged in line with the press, a web register correcting unit comprising first and second diagonal turning bars and their intermediate web reversing roller, means for passing the web through the first printing unit, around the first turning bar, the roller, the second turning bar and through the second printing unit, and means controlled by the lateral shifting of the web for automatically adjusting both ends of one of the turning bars to correct the loss of lateral register of the web and for

automatically and simultaneously adjusting both ends of the roller to correct the loss of longitudinal register of the web due to its correction for lateral register.

11. In a rotary web perfecting printing press, first and second printing units arranged in line with the press, a web register correcting unit comprising first and second diagonal turning bars and their intermediate web reversing roller, means for passing the web through the first printing unit, around the first turning bar, the roller, the second running bar, and through the second printing unit, and means controlled by the lateral shifting of the web for automatically adjusting both ends of the second turning bar to correct the loss of lateral register of the web and for automatically and simultaneously adjusting the roller to correct the loss of longitudinal register of the web due to its correction for lateral register.

12. In a rotary web perfecting printing press, first and second printing units arranged in line with the press, a web register correcting unit comprising first and second diagonal turning bars and their intermediate web reversing roller, means for passing the web through the first printing unit, around the first turning bar, the roller, the second turning bar and through the second printing unit, a photoelectric unit controlled by the lateral shifting of the web, and a motor controlled by the photoelectric unit and operatively connected to both ends of one of the turning bars to automatically adjust the said turning bar without changing its angularity for correcting the loss of lateral register of the web.

13. In a rotary web perfecting printing press, first and second printing units arranged in line with the press, a web register correcting unit comprising first and second diagonal turning bars and their intermediate web reversing roller, means for passing the web through the first printing unit around the first turning bar, the roller, the second turning bar and through the second printing unit, a photoelectric unit controlled by the lateral shifting of the web, and a reversible motor controlled by the photoelectric unit and operatively connected to both ends of one of the turning bars to automatically adjust the said turning bar without changing its angularity for correcting the loss of lateral register of the web in either direction.

14. In a rotary web perfecting printing press, first and second printing units arranged in line with the press, a web register correcting unit first and second diagonal turning bars and their intermediate web reversing roller, means for passing the web through the first printing unit, around the first turning bar, the roller, the second turning bar and through the second printing unit, a photoelectric unit controlled by the lateral shifting of the web, and a motor controlled by the photoelectric unit and operatively connected to both ends of one of the turning bars and the roller, to automatically adjust the said turning bar and the roller for correcting the loss of lateral and the consequent loss of longitudinal register of the web.

15. In a rotary web perfecting printing press, first and second printing units arranged in line with the press, a web register correcting unit comprising first and second diagonal turning bars and their intermediate web reversing roller, means for passing the web through the first printing unit, around the first turning bar, the roller, the second turning bar and through the second

printing unit, a photoelectric unit controlled by the lateral shifting of the web, and a reversible motor controlled by the photoelectric unit and operatively connected to both ends of one of the turning bars and the roller to automatically adjust the said turning bar and the roller for correcting the loss of lateral and the consequent loss of longitudinal register of the web.

16. In a rotary web perfecting printing press,
10 first and second printing units arranged in line
with the press, a web register correcting unit
comprising first and second diagonal turning
bars and their intermediate web reversing roller,
means for passing the web through the first
15 printing unit, around the first turning bar, the
roller, the second turning bar and through the
second printing unit, a photoelectric unit con-
trolled by the lateral shifting of the web, and
a motor controlled by the photoelectric unit and
20 operatively connected to both ends of the second
turning bar and the roller to automatically ad-
just the said turning bar and the roller for cor-
recting the loss of lateral and the consequent
loss of longitudinal register of the web.

25 17. In a rotary web perfecting printing press, first and second printing units arranged in line with the press, a web register correcting unit comprising first and second diagonal turning bars and their intermediate web reversing roller, 30 means for passing the web through the first printing unit, around the first turning bar, the roller, the second turning bar and through the second printing unit, a photoelectric unit controlled by the lateral shifting of the web, and a reversible 35 motor controlled by the photoelectric unit and operatively connected to both ends of the second turning bar and roller to automatically adjust the said turning bar and the roller for correcting the loss of lateral and the consequent loss of 40 longitudinal register of the web.

18. In a rotary web perfecting printing press, first and second printing units arranged in line with the press, a web register correcting unit comprising first and second diagonal turning bars and their intermediate web reversing roller, means for passing the web through the first printing unit, around the first turning bar, the roller, the second turning bar and through the second printing unit, manually operated means for initially adjusting the turning bars and roller, and means controlled by the lateral shifting of the web for automatically adjusting both ends of one of the turning bars to correct the loss of lateral register of the web.

55 19. In a rotary web perfecting printing press,
first and second printing units arranged in line
with the press, a web register correcting unit
comprising first and second diagonal turning bars
and their intermediate web reversing roller,
60 means for passing the web through the first
printing unit, around the first turning bar, the
roller, the second turning bar and through the
second printing unit, manually operated means
for initially adjusting the turning bars and roller,
65 and means controlled by the lateral shifting of
the web for automatically adjusting both ends of
the second turning bar to correct the loss of lat-
eral register of the web.

20. In a rotary web perfecting printing press,
70 first and second printing units arranged in line
with the press, a web register correcting unit
comprising first and second diagonal turning
bars and their intermediate web reversing roller,
means for passing the web through the first
75 printing unit, around the first turning bar, the

roller, the second turning bar and through the second printing unit, manually operated means for initially adjusting the turning bars and roller, and means controlled by the lateral shifting of the web for automatically adjusting both ends of one of the turning bars and the roller to correct the loss of lateral and the consequent loss of longitudinal register of the web.

21. In a rotary web perfecting printing press, first and second printing units arranged in line with the press, a web register correcting unit comprising first and second diagonal turning bars and their intermediate web reversing roller, means for passing the web through the first printing unit, around the first turning bar, the roller, the second turning bar and through the second printing unit, manually operated means for initially adjusting the turning bars and roller, and means controlled by the lateral shifting of the web for automatically adjusting both ends of the second turning bar and the roller to correct

the loss of lateral and the consequent loss of longitudinal register of the web.

22. In a rotary web perfecting web printing press, first and second printing units arranged in line with the press, means for passing the web through said printing units, and a web register correcting unit controlled by the lateral shifting of the web for automatically and simultaneously correcting the loss of lateral and the consequent loss of longitudinal register of the web as it passes from the first printing unit to the second printing unit, the web register correcting unit including two diagonal turning bars, their coacting web reversing roller, a scanning roller, a photoelectric unit having two scanning heads coacting with said scanning roller, and a motor set in motion by the photoelectric unit, said motor being operatively connected to both ends of one of said turning bars and to their coacting roller for simultaneously adjusting them.

JOSEPH E. MEYER.
